LOOM

Arthur Booth, Chicago, Ill.

Application March 8, 1947, Serial No. 733,319

10 Claims. (Cl. 139—30)

1
This invention relates to weaving looms and more particularly to looms of the portable manually operable type.

The main object of the invention is to provide a more efficient harness actuating means whereby the heddle frames may be more effectively operated.

The loom, according to the present invention, is basically similar to the majority of hand looms of this class in so far as the course of travel of the yarn or warp is concerned. Like other looms, the yarn leaves the warp beam which is situated at the rear of the frame and passes over a rear rail, then through the heddles and through a beater or reed, then over the front breast rail and then being wound around the cloth beam located at the front of the loom frame.

The harness frames, six in the disclosed embodiment of the invention, each carry an alignment of heddles and are raised and lowered by means of a system of under pivoted levers, instead of the usual practice of overhead ropes and pulleys. The lam which controls the actuation of the heddle frame through said under pivoted levers is actuated by a treadle to which it is connected by an adjustable link. Any number of these lams and links may be connected to a single treadle, which is provided with a series of openings to accommodate this purpose. The treadles are pivoted on a common shaft, and the entire assembly may be retracted into the body of the loom. A wing nut adjustment at the center of the vertical main member of the loom frame permits the loom to be folded or closed to provide a compact unitary structure whereby the loom may be readily transported.

The foregoing and other objects and features of the present invention will appear in the following detailed description when taken in conjunction with the accompanying drawings, 40 wherein:

Figure 1 is a perspective view of the loom in its operating position.

Fig. 2 is a top view of the shuttle.

Fig. 3 is a section on the line 3—3 of Fig. 2. 45

Fig. 4 is a section on the line 4—4 of Fig. 3.

Fig. 5 is a perspective view corresponding to Fig. 1 but showing the loom in its folded position.

Fig. 6 is a detail in perspective showing the means for facilitating the connection of the warp threads to the cloth beam.

Fig. 7 is a side elevation of the loom as viewed from the right of Fig. 1, with a modified treadle mechanism.

Fig. 8 is a sectional detail of the guides for the 55

heddle harness frames taken on the line 8—8 of Fig. 7.

Fig. 9 is a front elevation of the loom, with some parts broken away and some omitted, showing particularly the mechanism which connects the operating treadles with the harness frames.

Fig. 10 is a fragmentary rear elevation showing the structure of the warp beam and some of its operating mechanism.

Fig. 11 is a section of the warp beam taken on line 11—11 of Fig. 10.

Fig. 12 is a fragmentary detail of the counter gearing.

Having reference to Figs. 1, 7 and 9 of the drawings, the frame of the loom comprises spaced-apart base members 12 and 13 to which are secured vertically disposed side members 14 and 15, which in turn are rigidly held in predetermined spaced relation by front and rear cross members 16 and 17, and a top member 18.

A warp beam, indicated generally at 19, carries the supply of warp threads 20 and is rotatably carried on a shaft 21, Figs. 11 and 12, suitably journaled, as hereinafter described, in a pivoted frame comprising side rails 22—22, and a top rail 23. Side rails 22 are carried pivotally on bolts 24 at the rear of the base members 12 and 13. A front breast rail 25, over which the warp 20 travels in well-known fashion, forms a part of a pivotal frame comprising also a pair of side rails 26 and 27 to which said front rail 25 is attached by means of wing nuts 28. Side rails 26 and 27 are mounted pivotally on a shaft 29 at the front of the base members 12 and 13.

The pivoted frames comprising rails 23 and 25 are maintained in proper angular position with respect to the base members 12 and 13 by means of two pairs of side elements or braces 31 and 32 and a clamping means comprising a bolt and a wing nut 33, one such clamping device for each pair of braces 31 and 32. Each clamping device is adapted to be slidable in respective slots 34 in vertical side members 14 and 15 so that the wing nut 33, when loosened, permits the lowering of the side braces 31 and 32, as shown in Fig. 5, which in turn causes the angularly disposed rails or posts 22—22 and 26—27 to be pivoted into a substantially vertical position for storage purposes or to facilitate the transportation of the loom.

In Fig. 7 is illustrated the course of the warp thread 20 from the warp beam 19 about which the supply of warp is wound. The warp threads pass singly side by side over the rear rail 23, each warp thread 20 is then threaded through

the eye 46 of the heddle 35, a series of which is carried in each of a plurality of harness or heddle frames 36. The warp threads are then directed between the reeds 37 carried by a reed frame 38, and then over the front breast rail 25 to a cloth beam 39. A means for facilitating the introduction of a new warp comprises a bar 41 to which the warp threads 20 are secured, and cords 42 are attached to lacing loops 42.1 permanently attached to the cloth beam 39. The cords 42 are looped around the bar 41 and through the loops 42.1 as shown. Moreover, the cords 42 are of a length to extend from the cloth beam 39 up over the front breast rail 25 for the purpose of convenience in attaching the warp threads and of drawing the end of the warp and the woven cloth to the cloth beam 39 on which the cloth is to be wound.

The harness actuating means is shown in Figs. 7 and 9. As previously alluded to, the harness frames 36 support therein on upper and lower rods 43 and 44, a plurality of heddles 35. These heddles 35 are formed at each end with eyelets 45, through the instrumentality of which they are adapted to ride loosely on the rods 43 and 44. As more clearly shown in Fig. 9, the heddles 35 are provided intermediate their ends with eyelets 46 through which the warp is threaded.

The harness frames 36 are slidably mounted for vertical reciprocation in runways or tracks 47 disposed on the inner confronting surfaces of the side members 14 and 15. In the illustrated embodiment of Fig. 8, the tracks 47 are formed by inserting a U-shaped section of metal 48 inside of another U-shaped section of metal 49 of greater width so as to provide three tracks 47 of equal width. In the loom structure shown, two such track assemblies are provided, thereby accommodating six harness frames 36.

The harness frames 36 are adapted to be raised and lowered by means of a system of underpivoted levers 51 and 52 (Fig. 9). Each pair 51-52 is associated with a harness frame 36 and its respective lam 53. Each lam 53 is actuated by a treadle 54 in the form of a treadle lever to which the lam is connected by a link 55. The upper ends of these links are of hook formation to enable them to be readily shifted to engage apertures 56 in different lams 53. The links 55 are loosely slidable in apertures 57 in the treadle levers 54 and have nuts or heads 60 against which the treadle levers bear for transmitting motion to the lams 53.

Any number of lams 53 may be connected to a single treadle 54, which is provided with a series of openings 57 (Figs. 1 and 7) to accommodate links for this purpose. The treadles 54 comprise a metal bar 58 and a flanged hinge element 59 through which said treadles are pivotally supported on a common shaft 61 carried by a pair of side arms 62 which are in turn mounted pivotally on the shaft 29 and constitute a treadle supporting frame. Secured to each treadle portion 58 is a foot member 63. With the construction shown, the entire treadle assembly may be folded into the body of the loom, as illustrated in Fig. 5, without disconnecting the linkage between the pedals and lams.

Each lever of the pair of levers 51-52 is connected to its associated lam 53 by means of a link 69, and to its associated harness frame 36 by a link 70. Levers 51-52 are pivotally mounted in scissor-fashion upon a common stud shaft 71 fixed to frame bars 16-17. Thus, upon the actuation or depression of a treadle 54, the oper-

ated lam or lams 53 will be lowered, as will appear from Fig. 9, and the levers 51-52 will be rotated in opposite directions to raise, through links 70, the harness frame 36. The links 69 function as tension members whereby the lam 53 pulls down the corresponding arms of the levers 51 and 52 and the links 70 function as thrust members whereby the respectively opposite ends of the levers 52 lift the harness frame 36, which normally slides by gravity to its lowered position. With the present invention any number of lams 53 can be operated by a single treadle, and with the novel scissor arrangement of levers 51 and 52, the lam 53 is always parallel regardless of the point thereon where the pull of its link 55 is applied.

The reed frame 38 fits within a beater frame 64 pivotally mounted on pivots 65 to the base members 12 and 13. Reeds 37 are appropriately mounted in upper rail 66 and lower rail 67, the lower rail 67 being made wider to form a slide-way for a shuttle 68, Figs. 1 and 7.

The warp beam 19 (Figs. 1, 10 and 11) is composed of four removable slats 73 fitted into end pieces 74.1 through the center of which passes the shaft 21. Slats 73 are held in place by means of hook and eye instrumentalities 70. Each slat 73 is provided with a longitudinal row of pegs 74, which are also disposed so as to provide circumferential rows, thus producing suitable spacing for warp threads of different colors. The shaft 21 is journaled on side rails 21 and 22, and a handle 75 is adapted to fit into one end thereof as shown in Fig. 10 to enable the warp beam 19 to be manually rotated to unwind the warp threads 20 at appropriate times.

A ratchet 76 is secured to the warp beam and a detent pawl 77 cooperates therewith. Pawl 77 is slidably supported in a guide member 78 mounted on the inside face of rail 21 and to said pawl 77 is attached an operating cord 79 which extends through eyelets 81, 82 and 83 and terminates in a handle 84. The purpose of cord 79 and pawl 77 is to release the warp beam 19 for rotation to release a new supply of warp threads. Secured to handle 75 is a gear tooth 85 which acts upon each revolution of the warp beam 19 to operate an indicator gear member 86 so adjusted as to indicate the approximate amount of warp thread released from the warp beam. This indication may be represented by dial characters on the face of gear 86, as for example, numerals such as 19, 20, 1, 2, and 3 shown in Fig. 12.

The cloth beam 39 is journaled in a pair of brackets 87 extending from front cross member 16. Fastened to the cloth beam 39 is a ratchet wheel 88 which cooperates with a detent pawl 89 suitably mounted on the bracket 87 adjacent the ratchet wheel 88. Carried in an extension 60 of the cloth beam 39 is a handle 91 by means of which clockwise rotation may be imparted to wheel 88 and beam 39 to take up the woven fabric as it is finished.

In Fig. 7 is shown a modified form of treadle 92 which comprises a metal bar 93 offset to accommodate the adjustable ends of the links 94 which are provided with nuts and lock nuts for adjusting purposes. The bar 93 is formed with depending flanges through which the treadles 92 are pivotally supported on the common shaft 61 journaled in the side arms 62, as previously described. Secured to each bar 93 is a foot board 96.

Having reference to Figs. 7 and 10, the shaft 21 is shown journaled at each end in sleeve members 97 and 98, preferably enveloping and slidably

mounted on side rails 22. The rails 22 are provided with slots 99 to accommodate the ends of shaft 21 in the slideable movement of members 15 and 16. Each sleeve member 97 and 98 is provided with an inwardly extending lug portion 100 to which is secured one end of a spring 101, the other end of which is secured to the underside of rail 23.

The pull of springs 101 is balanced by a brake mechanism comprising a brake band 102, a spring 103 and a sheave 104. Brake band 102 comprises a strap which is secured at one end to a bolt 105 mounted on side rail 22, and then passes around the sheave 104, the other end of the brake band 102 being attached to one end of the spring 103. The other end of spring 103 is anchored suitably to the side rail 22. A warp guide 113 is mounted on rail 23 so as to be freely slideable therewith.

A suitable form of shuttle is shown in Figs. 2, 3 and 4. Spool 106 of woof thread is wound on a spindle 107 and is inserted into a side aperture in the body of the shuttle 68 which is hollowed out for the purpose and which has seats 108 and 109 at its opposite ends for the ends of the spindle. Adjacent the seat 109 is a bore 110 which houses a plug 111 that is split at 112 at its free end and which serves as a snap lock for securing the spindle 107 in place. The inner end of the plug is fast in its socket and the upper split portion of the plug is free to expand to allow the spindle to be snapped into or out of the cross bore that provides a seat.

In the operation of the loom of the present invention, it is assumed that the loom has been folded to the position shown in Fig. 5, wherein the parts are maintained in the collapsed or folded position by reason of the tightening of the wing nuts 33. Moreover the treadles 54 have been swung to the position shown in Fig. 5 which demonstrates the compact arrangement of which the loom according to the present invention is capable. The shuttle 68 is carried on the shelf 18.

Now, to bring the loom into operative condition, the wing nuts 33 are loosened and the braces 31 and 32 are caused to assume the horizontal aligned position shown in Fig. 1, whereby the pivoted frames carrying the warp beam 19 and the front breast rail 25 are permitted to rotate on their respective shafts 24 and 29 to assume outwardly inclined positions. The warp threads 20 are then threaded through the loom as previously described preparatory to weaving the fabric. The treadles 54 are rotated to their operating position.

In the operation of weaving, the shuttle 68 is shifted back and forth through the shed. The shed is changed each time the shuttle is passed therethrough, by operating the treadles 54 in accordance with a predetermined sequence or permutation to produce the desired woven effect. The batten or reed 38 is manipulated in the customary manner to press the weft threads together, as is well known in the art.

The warp guide 113 is in the form of an upstanding plate of a width approximating the spacing of the pegs 74 on the warp beam and having a multiplicity of holes 114 through which warp threads are guided during the initial operation of mounting a supply of them on the warp beam. The guide plate 113 is attached to the rail 23 as by a sleeve 115 that is slideable along the rail 23 and is thus adjustable along the rail for guiding the supply of warp threads between any pair of the pegs 74.

The harness frames 36 normally occupy positions at the lower limit of their movement in the

track ways 47, resting upon stops, not shown, and with their respective banks of warp threads 20 down so that they lie across the ledge bar 67 in the lower position shown in Fig. 7. When one of the treadles 54 is depressed, the lam or lams 53 to which such pedal is linked will operate the corresponding pair or pairs of levers 51—52 and raise the corresponding harness frame or frames 36 to carry the corresponding warp threads 20 to the raised position shown in Fig. 7, thus opening the proper shed for passage of the shuttle 68. Each lam 53 remains level, due to its connections through its respective levers 51 and 52 with its respective harness frame 36, regardless of where the pull of its link 94 is applied.

Although specific arrangements of the invention have been described, it is understood that details may be altered or omitted without departing from the spirit of this invention and that all forms which come within the scope and equivalency of the appended claims are intended to be embraced therein.

I claim:

1. A loom comprising a main upright frame, a vertically disposed heddle frame vertically slideable in said main frame, a horizontally disposed lam below and substantially in the plane of movement of said heddle frame, a pair of levers pivoted between their ends in scissor-fashion on a common stationary axis transverse to the plane of said heddle frame and having their respective opposite corresponding arms respectively linked directly to said heddle frame and to said lam for imparting opposite parallel motions to said lam and heddle frame, and a treadle lever linked to said lam.

2. A loom comprising a main upright frame, a vertically disposed heddle frame vertically slideable in said main frame, a horizontally disposed lam below and substantially in the plane of movement of said heddle frame, a pair of levers pivoted between their ends in scissor-fashion on a common stationary axis transverse to the plane of said heddle frame and having their respective opposite corresponding arms respectively linked directly to said heddle frame and to said lam for imparting opposite parallel motions to said lam and heddle frame, a treadle supporting frame swingable between a horizontally extended position and an upright position on said main frame, and a treadle lever pivoted at the free end of said treadle frame and linked to said lam.

3. A loom, comprising a main upright frame, a plurality of heddle frames vertically shiftable in said main frame, harness mechanism comprising a pair of levers and a lam bar for each said heddle frame, each such pair of levers and lam bar being located below and substantially in the same vertical plane with the respective heddle frame, the members of each pair of levers being pivoted for relative movement in scissor-fashion on a common axis normal to the plane of movement of the heddle frames and having their respectively opposite corresponding arms respectively linked directly to their said heddle frame and lam bar for imparting opposite parallel motions thereto, a treadle supporting frame hinged to said upright frame and swingable between an outwardly extended horizontal position and an upright position, a plurality of treadle levers hinged on said treadle supporting frame and extending crosswise of and below said lam bars and arranged in a series lengthwise of said lam bars, and linkage means for connecting each said treadle to said lam bars selectively,

said linkage means being slidably connected to said treadle levers to permit said treadle supporting frame to be freely swung to its upright position without discontinuing said linkage means.

4. A loom comprising a supporting frame having spaced vertical guide ways at opposite sides thereof, a heddle frame vertically slideable along said guide ways, a horizontally disposed lam below and substantially in the plane of movement of said heddle frame, a pair of levers pivoted between their ends in scissor-fashion on a common stationary axis transverse to the plane of said heddle frame and having their respectively opposite corresponding arms respectively thrust linked to said heddle frame and tension linked to said lam for imparting opposite parallel motions to said lam and heddle frame, and a treadle lever linked to said lam.

5. A loom comprising a main upright frame, a vertically disposed heddle frame vertically slideable in said main frame, a horizontally disposed lam below and substantially in the plane of movement of said heddle frame, a pair of levers pivoted between their ends on a common stationary axis transverse to the plane of said heddle frame, said levers each having one arm connected to said heddle frame and its other arm connected to said lam, for transmitting parallel motion from said lam to said heddle frame through scissor-fashion movement of said levers, the connection between said levers and heddle frame comprising thrust members, and the connections between said levers and lam comprising tension members, and treadle lever linked to said lam.

6. A loom comprising a main frame, a harness frame vertically reciprocable relative to said main frame, mechanism including a treadle for raising said harness frame, a rear rail frame and a breast rail frame at opposite sides of said harness frame and pivotally mounted at their lower ends on said main frame, means connecting said rail frames to said main frame movable from a position holding said rail frames spread apart in operative position to a position holding said rail frames in folded position and means carrying said treadle and movably mounted on said main frame from a position supporting said treadle in extended operative position to a position supporting said treadle in retracted position approximately within the vertical confines of said main frame.

7. A loom comprising a main frame, a harness frame vertically reciprocable relative to said main frame, mechanism including a treadle for raising said harness frame, a rear rail frame and a breast rail frame at opposite sides of said harness frame and movably mounted on said main frame from an operative position to a folded position and means carrying said treadle movably mounted on said main frame to carry said treadle in extended operative position when said rail frames are in operative position and to carry said treadle in retracted position when said rail frames are in folded position.

8. A loom comprising a main frame, a harness frame vertically reciprocable relative to said main frame, and mechanism located below the top of said harness frame for raising said harness frame, said mechanism comprising a pair of levers pivotally mounted between their ends on said main

frame, said levers being below said harness frame and extending substantially parallel to the plane of movement of said harness frame, each of said levers having one arm connected to said harness frame, a floating lam below said levers and extending substantially parallel to the plane of movement of said harness frame, connections between said lam and the other arm of each of said levers, and a treadle below and connected to said lam intermediate the connections between said lam and levers.

9. A loom comprising a main frame, a harness frame guided by and vertically reciprocable relative to said main frame, and mechanism located below said harness frame for raising the same, said mechanism comprising a pair of levers located below said harness frame and extending substantially parallel to the plane of movement of said harness frame, said levers being pivotally mounted between their ends on said main frame, a lam below said levers and extending substantially parallel to the plane of movement of said harness frame, links between said harness frame and corresponding ends of said levers, links between the other ends of said levers and said lam, said last-mentioned links carrying said lam from said levers, a treadle below and extending transversely of said lam and means connecting said treadle to said lam intermediate said last-mentioned links for lowering said lam upon depression of said treadle.

10. A loom comprising a main upright frame, a vertically disposed harness frame vertically slideable in said main frame, a horizontally disposed lam below and substantially in the plane of movement of said harness frame, a pair of levers below and substantially in the plane of movement of said harness frame and pivoted between their ends on said main frame, said levers each having one arm connected to said harness frame and the other arm connected to an end of said lam for transmitting parallel motion from said lam to said harness frame, the connections between said harness frame and levers comprising thrust members and the connections between said levers and lam comprising tension members, and a treadle below and extending transversely of said lam and operatively connected to said lam between its ends.

ARTHUR BOOTH.
